UNITED STATES PATENT OFFICE.

ELMER E. BUMPUS, OF KALISPELL, MONTANA.

HOT-AIR-CIRCULATING FIREPLACE.

1,175,122.

Specification of Letters Patent. Patented Mar. 14, 1916.

Application filed June 9, 1915. Serial No. 33,134.

To all whom it may concern:

Be it known that I, ELMER E. BUMPUS, citizen of the United States, residing at Kalispell, in the county of Flathead and State of Montana, have invented a new and useful Hot-Air-Circulating Fireplace, of which the following is a specification.

This invention relates to an improvement in hot air circulating fire places, and the object is to provide an air space or chamber, between the chimney and the fire place and flue, for the purpose of utilizing the heat thrown off by the fire place and the flue as the products of combustion pass up through the flue and chimney. Inlet openings are formed in the chimney for admitting air from any suitable source, such as from a room to the air chamber, where it will be heated. After the air has been heated it can be discharged through ducts, these ducts being closed by registers for controlling the admission of heat to a room or rooms.

A further object is in the construction of a removable fire place, wherein the sides and back can be removed for the purpose of replacing any of the parts that may become defective by warping or cracking.

Another object is in the provision of means for supporting a flue, which is independent of the fire place, so that the various sections of the fire place can be removed without affecting the flue.

The invention consists of certain novel features of construction and combinations of parts, which will be hereinafter described and pointed out in the claims.

It is evident that many slight changes may be made in the form and arrangement of the several parts to be described, without departing from the spirit and scope of the invention, and hence I do not wish to be limited to the exact construction herein set forth.

In the accompanying drawings,—Figure 1 is a transverse vertical sectional view. Fig. 2 is a longitudinal vertical sectional view with a portion of the chimney shown in elevation to indicate the manner of mounting the registers. Fig. 3 is a horizontal sectional view. Fig. 4 is a horizontal sectional view on the line 4—4 of Fig. 2. Fig. 5 is a detail longitudinal sectional view through the back and side of the fire place. Fig. 6 is an enlarged detail vertical sec-

tional view through the chimney and flue to show the manner of supporting the flue and damper. Fig. 7 is a perspective view of an end of one of the back sections.

A represents the chimney, which may be constructed of brick, stone, concrete, cement, and the like. The chimney is provided with the usual opening, but in this instance an enlarged opening is provided in which a fire place is mounted. The fire place is constructed of a base 1, made in sections, the two sections being supported by means of posts or standards 2. A flange 3 is formed on one of the sections of the base for forming a tight joint between the adjoining edges of the two sections. Parallel flanges 4 are formed along the rear edge of the base 1, between which is received one of the sections or plates 5 of the back. Each of the back plates 5, with the exception of the uppermost plate, are provided along one of their longitudinal edges with parallel flanges 6. A longitudinal groove is formed between the parallel flanges of each back plate, in which groove the lower longitudinal edge of the adjacent back plate is received. Side members 7 are mounted upon the base 1 and are held in position by means of flanges 8 formed on the base along the outer edges thereof. Pins 9 are adapted to enter openings formed in the base for holding the side members against the flanges 8 for supporting the sides. The inner vertical edges of the side members engage the inner faces of the several back plates 5, and flanges 10 on the back plates engage the exterior surfaces of the side members. Ears 11 are formed on the side members 7 at suitable intervals, and are adapted to engage the back plates 5. Bolts 12 pass through the ears and back plates, and nuts 13 are screwed upon the bolts for fastening the side members and back plates together.

Angle iron bars 14 are mounted within the chimney, and extend across the upper edge thereof, above the opening 15 of the fire place. An angle iron bar 16 extends across the fire place and is engaged by the upper terminal of the uppermost back plate 5. The upper terminals of the side members 7 are located between the angle iron bars 14 and the uppermost back plate 5, so that the side members and back are maintained in position at their upper terminals by the bars 14 and 16. The flue 17 is supported upon

the bars 16 and 14 so that the products of combustion will pass directly from the fire place into the flue 17.

The base 1 of the fire place is provided with an opening, which is normally closed by a cap or lid 18, an outlet pipe 19 being in communication with the opening through which the ashes may be discharged. A damper 20 is suitably connected to the uppermost angle iron bar 14, and is adapted to rest upon the bar 16 for closing the flue 17. A flexible means, such as a chain 21, is connected to the damper 20, and extends through the flue 17, and a tube 22 which projects through the breast or front side of the chimney. A slot 23 is formed in the outer terminal of the tube 22 in which a link of the chain 21 may be received for holding the damper in an open or partially open position.

Surrounding the fire place is an air chamber B, which extends across the back and on both sides of the fire place, as well as below the fire place. This air chamber is continued for a distance vertically of the chimney and entirely around the flue 17.

An outlet conduit 24 is formed in the fire place for conducting the heat from the air chamber to a room, and outlet conduits are formed in the chimney leading from the chamber or air space B at various points, as indicated at 25 and 26. These several openings 24, 25 and 26 are preferably provided with registers 27, which are capable of being regulated for controlling the admission of heated air to the room. Air inlet pipes 28 extend through the fire place for admitting air to the air chamber B. These inlet pipes 28 may be located at any suitable place in the fire place for the purpose of conducting the cold air from a room, or the atmosphere to the air chamber B. With a fire place constructed in this manner having an air chamber located therearound, and extending vertically through the chimney and around the flue, it is possible to utilize the waste heat from the fire place and chimney. By means of a fire place constructed of a plurality of sections, as set forth, wherein the back is composed of a plurality of interlocking plates, and the side members are removably connected to the back plates, it is possible to maintain the entire structure in a rigid condition and to remove any of the back or side plates at any time they become defective caused by cracking or warping. The fire place is independent of the flue and can be taken down and repaired at any time without disturbing the flue or damper. The surface of the plates 5 is preferably flat and the plates extend from the rear edge of the base 1 to the bar 16 at an angle, so that the heat will be deflected into the room but the products of combustion will be caused to pass into the flue 17.

What is claimed, is,—

1. In combination with a chimney open at its lower end, a removable back placed in the chimney, removable sides detachably engaging the back, a damper hinged in the chimney at the top of the sides and back, and an angle bar arranged transversely in the chimney engaging the back and sides to support the same, and adapted to support said damper when turned down into closed position. 70

2. In combination with a chimney open at its lower end, a removable back placed within the chimney, removable sides detachably connected to the back, a flue extending upwardly in the chimney, a damper hinged in the chimney at the bottom of the flue, and an angle bar arranged transversely in the chimney to support the upper ends of said back and sides, to support said flue and relieve the back and sides from the weight thereof, and to support said damper when lowered into closed position. 80

3. The combination of a chimney having an opening therein, a fire place mounted in the opening, said chimney and fire place having an air chamber formed therebetween, said fire place consisting of a base, sides and sectional back, means for connecting the back and sides together, bars connected to the chimney for engaging the upper terminals of the sides and back, a flue in communication with the fire place supported upon said bars, means for controlling the admission of the products of combustion to the flue, said chimney provided with outlets for conducting the heated air from the air chamber. 90

4. The combination of a chimney having an opening therethrough, a fire place mounted therein, consisting of a base, side members and back plates, angle iron bars mounted in the chimney being engaged by the side members and back plates for supporting them, and a flue in communication with the fire place mounted on said bars independently of the side members and back plates of the fire place, whereby the fire place can be repaired without removing the flue. 100

5. In combination with a chimney open at its lower end, of a fire place spaced inwardly from the walls of the chimney, and a flue leading upwardly through the chimney in spaced relation to the walls thereof from the fire place, said fire place comprising a plurality of separable sections, and a transverse bar in the chimney at the bottom of the flue for supporting the said sections when assembled and for supporting said flue and relieving the weight thereof from said sections, said transverse bar adapted to support the flue during the removal and adjustment of said fire place sections. 110

6. The combination with a chimney hav- 11

ing an opening, of a fire place mounted therein consisting of a base, side members and back plates, an angle iron bar mounted in the chimney engaging the back plates for holding them in position, and a flue mounted on and supported by the angle iron bar.

In testimony, that I claim the foregoing

as my own, I have hereto affixed my signature in the presence of two witnesses.

ELMER E. BUMPUS.
